[57] CLAIM

The ornamental design for a self-standing floor sign, as shown and described.

DESCRIPTION

FIG. 1 is a front perspective view of a self-standing floor sign showing our new design.

FIG. 2 is a rear perspective view thereof.

FIG. 3 is a front elevational view of the front panel.

FIG. 4 is a side elevational view showing the front and rear panels folded together.

FIG. 5 is an enlarged fragmentary sectional view on line 5—5 of FIG. 3.

FIG. 6 is an enlarged sectional view on line 6—6 of FIG. 4.

FIG. 1

FIG. 5

FIG. 6
